No. 827,847.

Specification of Letters Patent.

Patented Aug. 7, 1906.

Application filed January 23, 1905. Serial No. 242,253.

To all whom it may concern:

Be it known that I, CHARLES E. BROOKS, a citizen of the United States, and a resident of the city of St. Louis, in the State of Missouri, have invented a new and useful Improvement in Presses, of which the following is a specification.

My invention relates to presses, and especially to embossing and printing presses.

It has for its principal objects to provide die-reciprocating mechanism comprising a continuously-moving part and allowing the die a period of rest at one extremity of its movement; to provide an eccentric transmission having an idle point in its cycle of operations; to provide driving mechanism for the press cross-head having intermittent actuating engagement with the cross-head; to provide means to cushion the actuating engagement of the driving mechanism with the cross-head; to provide a positive and adjustable stop for the die-carrying member to properly position it during its period of rest, and other objects hereinafter more fully appearing.

My invention consists in the parts and in the arrangements and combinations of parts hereinafter described and claimed.

In the accompanying drawings, forming a part of this specification, and wherein like symbols refer to like parts wherever they occur, Figure 1 is a front view of the press, the wall of one dash-pot being broken away. Fig. 2 is a side view. Fig. 3 is a central vertical sectional view. Fig. 4 is a central sectional view through one of the dash-pots. Fig. 5 is a sectional view through one of the columns of the frame. Fig. 6 is a side view of the eccentric and strap. Fig. 7 is a sectional view on the line 7 7 of Fig. 8. Fig. 8 is a vertical sectional view through the eccentric and strap on the line 8 8 of Fig. 7. Figs. 9, 10, and 11 are views similar to Figs. 6 to 8 of a modified form of eccentric and strap; and Fig. 12 is a view similar to Fig. 11, showing the position of the parts after a half-revolution.

From a base 1 rise hollow columns 2 2, which are connected intermediate of their ends by a beam 3. Below the beam 3 a member 4 extends between the columns and constitutes the front portion of a bed-plate 5. The bed-plate is supported at its rear end by small columns 6 6. The columns 2 2

have widely-separated bearings on the base. 55 These parts form the frame of the machine.

The bed-plate 5 is provided with grooves 7, in which a table 8 reciprocates. The table is adapted to receive an embossing and printing die 9 or a printing-plate, which may 60 be secured in any manner desired. Coöperating with said die is a platen or corresponding die 10, which is secured to plunger 11. The plunger in turn is secured to a cross-head 12 by means of a screw-threaded shank 65 13 and nuts 14 15, one of which works in a slot in the cross-head and the other of which is arranged below the cross-head and serves as a set-nut. The ends of the cross-head extend through the bifurcated upper ends of 70 the columns 2 2. Guide-rods 16 16 are secured to the cross-head and move with it. The end of said guide-rods are guided by bearings in the columns. Springs 17 17 surround the guide-rods 16 16 and support 75 the cross-head, tending to hold it in its uppermost position. They rest at their lower ends upon adjustable seats 17^a, whereby the tension of the springs can be adjusted and springs of different lengths can be accommodated. 80

In embossing and printing press work it is the common and most satisfactory practice to make the lower die 9, which is generally an intaglio-die, of steel or the like, and case-harden it, then to use pasteboard or the like for the platen, which is "hammered up" to form the corresponding die or relief. So long as the two dies always come together in the same relative position the work will be satisfactory; but obviously the slightest variation will result in the destruction of the upper die. To ink and wipe the lower die 9, it is moved rearwardly from beneath the upper die or platen. No inking and wiping mechanism are shown, as any such mechanism desired can be mounted over the bed-plate, the operation of the parts shown being in no way affected by the inking and wiping mechanism. The lower die 9 must move from the rear forwardly under the inking and wiping mechanism and then under the plunger and upper die or platen and stop there while the plunger makes contact with it and retires. The die must be accurately positioned in the same 95 place at every reciprocation, must be firmly held there, and must not move during the period of contact with the upper die or 100 105

platen, and the upper die or platen must be reciprocated so as to engage the lower die during its period of rest. To accomplish these desiderata, the following mechanism is provided: Upon the lower side of the table a block 18 is secured. It is provided with a slightly-conical bore 19, in the bottom of which is a block 20, preferably of wood. A pin 21 is secured in the frame in alignment with the bore of the block. The pin has a screw-threaded section which engages a screw-threaded counterbore in the frame. Thus the pin can be adjusted to different positions and can be set in any position by a set-nut 22. The rear end of the pin is slightly conical to correspond to the bore 19 in the block. The pin is adjusted so that it will stop the table and die in their most forward position or position of rest. The conical shape of the pin and bore results in drawing the table tightly down on its ways, and thus prevents the impact of the table on the ways when the platen strikes the die, which often occurs when the table is confined only by the ways. When the bore is worn, it is only necessary to shave the block 20 and advance the pin 21 a corresponding amount. The pin will thus be permitted to enter the bore far enough to compensate for the wear. A lever 23 is pivoted at its lower end upon the base 1. Its upper end is connected to the table 8 and die 9 by means of a link 24, which is pivotally connected with the block 18. This lever is oscillated about its pivot or fulcrum on the base by means hereinafter described. It is noted here that the manner in which the lever is connected to the table permits a slowing up of the movement of the table as it approaches its stopping-point. As the table begins its forward movement it moves substantially as rapidly as the upper end of the lever; but as the table approaches its stopping-place the movement of the upper end of the lever relative to the table (permitted by the link) is continually increasing, and hence its entire movement is not transmitted to the table. This will clearly appear from a comparison of the parts in the position shown in full lines in Fig. 3 with the position shown in dotted lines. As will appear below, the parts actuating the lever impart to it a movement diminishing in speed as it approaches its foremost position. A power-shaft 25 is mounted in the bifurcated lower ends of the columns. It may be actuated by any suitable source of power. Parallel with said power-shaft a main shaft 26 is journaled. Motion is communicated to the main shaft by means of a pinion 27 on the power-shaft meshing with a spur-gear 28 on the main shaft. An eccentric 29 is keyed on the main shaft 25 between the columns 22 and in the vertical plane of the pin 21, block 18, lever 23, and link 24. The eccentric is made in two parts

meeting in the diametral line extending through the point of maximum eccentricity and secured together by bolts. When the two parts are assembled, the eccentric consists of parallel disks connected at one side by a part having a substantially semicylindrical bearing-surface 30. This bearing-surface has an angular extent of slightly less than one hundred and eighty degrees to permit relative movement of the eccentric and strap at the time the roller hereinafter described enters the recess hereinafter described. At the side of the disks opposite the main shaft a roller 31 is journaled. This roller is so located that its outermost point lies in the continuation of the cylindrical surface, of which the bearing-surface 30 forms a part. Thus the eccentric has a discontinuous periphery. Surrounding the eccentric and lying between the disks thereof is an eccentric-strap 32. The greater portion of the bearing-surface of the eccentric-strap is cylindrical, as usual. At one point, however, there is a recess 33. The bearing-surface of this recess conforms to the path of the bearing-surface of the roller 31. Thus from the time the roller enters the recess the eccentric-strap will cease to be advanced by the eccentric and will not be again advanced or retracted until the roller moves out of the recess. Therefore this recess forms an idle point in the transmission of movement from the eccentric to the eccentric-strap. On each side of the strap are small bearing-blocks 34, bearing on the edges of the disks of the eccentric to prevent dropping of the eccentric-strap when the roller enters the recess.

The eccentric-strap is connected with the lever 23 by means of a substantially V-shaped frame 35, an eyebolt 36 being pivoted on a bolt in the lever and connected to the frame by means of nuts.

The recess 33 in the eccentric-strap is so located that the idle point occurs just when the table and die have reached their foremost position, and the recess is so proportioned that the period of the idle point is sufficient to permit the engagement of the plunger or platen with the die before the latter begins its rearward movement.

The construction described above results in an effectual locking of the table during its period of rest. As the roller is constantly in engagement with the bearing-surface of the recess, rearward movement of the eccentric-strap and table during the period of rest cannot occur. As the blocks 18 and 20 are in engagement with the pin 21, forward movement of the table cannot occur. Thus it is insured that there shall be no movement of the table during the time the impression is being made.

The mechanism for reciprocating the cross-head 12 and the connected plunger 11 and platen or die 10 will now be described.

The spur-gear 28 is provided with a wrist-pin 37. Upon the end of the main shaft 26 opposite to the spur-gear 28 a disk 38 is secured. A wrist-pin 39 is provided on said 5 disk.

The cross-head 12 terminates at its ends in journals 40, pierced by holes 41. The dimensions of said holes transverse to the journals increase in diameter from the horizontal 10 diameter upwardly and downwardly for a purpose hereinafter appearing. Sleeves 42 are journaled on the journals 40 and are provided with vertical bearings and dash-pots 43. Each dash-pot is provided with a pet- 15 cock 44, by means of which the rate of escape of air from the dash-pot can be regulated. A vertical groove 45 is provided in the wall of the dash-pot in line with the petcock and extends to the bottom of the dash-pot. In 20 the bottom of the dash-pot annular rubber cushions 46 are countersunk.

Pitmen 47 47 are journaled at one end on the wrist-pins 37 39, respectively, and extend upwardly through the bearings in the sleeves 25 42, the holes in the journals 40 on the ends of the cross-head, and through the dash-pots 43. The pitmen thus have a rocking bearing on the cross-head. A disk 48 is secured at the upper end of each pitman by means of a 30 nut. These disks constitute pistons co-operating with the dash-pots. The disks are provided with a peripheral flange 49, which is so located as to enter the groove containing the annular rubber cushions and bear upon the 35 latter.

The springs normally hold the cross-head in its uppermost position. As the main shaft rotates the pitmen are carried downwardly. The pistons enter the dash-pots, 40 and the air therein is gradually compressed. Thus the force acting upon the cross-head is gradually increased. When the pistons reach the bottom of the dash-pots, the peripheral flanges 49 engage the rubber cushions 46, 45 and the impact of the pitmen on the cross-head is thus further cushioned. Finally, the faces of the piston will engage the metallic bottoms of the dash-pots and further relative movement of the pistons and dash-pots ceases 50 until after the return stroke has been begun, when the above operations are reversed. The cross-head may have begun its downward movement before the pistons touch the metallic bottoms of the dash-pots; but in any 55 event there is no sudden impact, with its consequent jarring and vibration of the machine.

The wrist-pins are so located on the main shaft and the length of the pitmen is so 60 fixed that the cross-head, plunger, and die or platen will reach their lowermost positions during the period of rest of the table and die in their foremost positions.

While the form of eccentric described 65 above is the preferred form, other specific

forms can be used. A modification is shown in Figs. 9 to 12. In this form for the cylindrical bearing-surface two rollers 50 50 and a small sliding bearing 51 are substituted. A roller 52, corresponding to the roller 31 of the preferred form, is also provided. This latter roller is narrower than the rollers 50 50. The recess 53 in the eccentric-strap is a pocket. The rollers 50 50 pass over the recess as they engage the bearing-surface at each side 70 of the pocket. The narrower roller 52, however, enters the recess or pocket with the same result is in the preferred form of eccentric. 75

As shown, no change need be made in the eccentric-strap to use it with the modified form of eccentric. It is obvious, however, that when the preferred form of the eccentric is used the recess in the eccentric-strap may extend over the full width of the eccentric- 80 strap, as the angular extent of the recess is less than the angular extent of the semicylindrical bearing-surface, and hence the latter cannot enter the recess. 85

Obviously my machine is capable of considerable modification within the scope of my invention, and therefore I do not wish to be limited to the specific construction shown and described. 90

What I claim as my invention, and desire 95 to secure by Letters Patent, is—

1. In an embossing-press, the combination with a reciprocating die, of a plunger co-operating therewith, a driven shaft, and pitman-rods driven from said shaft and making 100 sliding connection with said plunger.

2. In an embossing-press, the combination with a reciprocating die, of a plunger co-operating therewith, a driven shaft, pitman-rods driven from said shaft and making sliding connection with said plunger, and cushions of resilient material between said pitman-rods and said plunger. 105

3. In an embossing-press, the combination with a reciprocating die, of a plunger co-operating therewith, a driven shaft, pitman-rods driven from said shaft and making sliding connection with said plunger, and springs 110 supporting said plunger.

4. In an embossing-press, the combination with a reciprocating die, of a plunger co-operating with said die, a cross-head carrying said plunger, guide-rods passing through said cross-head, springs surrounding said rods and supporting said cross-head, a driven 115 shaft, and pitman-rods driven from said shaft and making sliding connection with said cross-head.

5. In an embossing-press, the combination with a platen, of a reciprocating die, a 120 shaft, an eccentric on said shaft, an eccentric-strap surrounding said eccentric and provided with a recess forming an idle point, and operating connections between said eccentric-strap and die. 125

6. In a press, a frame, a cross-head reciprocatingly mounted in said frame, sleeves journaled on said cross-head and provided with bearings extending transversely to the cross-head, a main shaft, pitman-rods connected to said shaft and slidingly mounted in the bearings in said sleeves and means on said pitman-rods to engage said sleeves during a portion of the movement of said pitman-rods.
7. In a press, a frame, a cross-head reciprocatingly mounted in said frame, means to normally hold said cross-head at one extremity of its path, a main shaft, sleeves journaled on said cross-head and provided with bearings extending transversely to the cross-head, a main shaft, pitman-rods connected to said shaft and slidingly mounted in the bearings in said sleeves, means on said pitman-rods to engage said sleeves during a part of the movement of the pitman-rods, and means to cushion the impact of said means and said sleeves.
8. In a press, a frame, a cross-head reciprocatingly mounted in said frame, a shaft, pitman-rods connected to said shaft and said cross-head and having a sliding connection with the latter, and means to cushion the impact of each of said pitman-rods on said cross-head comprising a dash-pot and a piston, one of which is connected to the cross-head and the other of which is connected to the pitman-rod.
9. In a press, a frame, a cross-head reciprocatingly mounted in said frame, means to normally hold said cross-head at one extremity of its path, sleeves journaled on said cross-head and provided with dash-pots, resilient cushions seated in the bottoms of said dash-pots, a main shaft, pitman-rods connected to said shaft and slidingly engaging said sleeves and cross-head, and pistons on said pitman-rods in position to enter said dash-pots and engage said cushions.
10. In a press, a frame, a cross-head reciprocatingly mounted in said frame, springs to normally hold said cross-head at one extremity of its path, adjustable seats for said springs, a main shaft, and pitman-rods connected to said main shaft and slidingly connected with said cross-head.
11. In a press, a frame, a die-receiving member reciprocatingly mounted in said frame, a stop for said die-receiving member adjustably mounted in said frame, and means to reciprocate said die-receiving member comprising an eccentric having a discontinuous periphery and an eccentric-strap having a recess provided with a bearing-surface conforming to the path of the bearing-points of the eccentric in the region of maximum eccentricity, whereby said slide is given a period of rest and is securely held against movement during such period.
12. In a press, a frame, a die reciprocatingly mounted in said frame, a plunger co-operating with said die, means to reciprocate said plunger, means to reciprocate said die comprising an eccentric and an eccentric-strap having a recess forming an idle point, said recess being so located as to be effective when said die is in alinement with said plunger, and a stop adjustably mounted in said frame to position said die in alinement with said plunger.
13. In a press, a frame provided with ways, a die-receiving member reciprocatingly mounted in ways in said frame, means to reciprocate said die-receiving member, a stop adjustably mounted in said frame, a member on said die-receiving member to co-operate with said stop, the meeting portions of said stop and said member having corresponding frusto-conical surfaces, whereby said die-receiving member is held firmly to its ways.
14. In a press, a frame provided with ways, a die-receiving member reciprocatingly mounted in said ways, means to reciprocate said die-receiving member, a stop mounted in said frame, a member on said die-receiving member to co-operate with said stop, said stop and said member having interlocking engagement with each other and one of them being adjustable, whereby said die-receiving member is held firmly to its ways.
- In testimony whereof I have signed my name to this specification, in the presence of two subscribing witnesses, this 21st day of January, 1905, at St. Louis, Missouri.
